Primary Examiner — Catherine S Posthauer*(74) Attorney, Agent, or Firm* — Husch Blackwell LLP(57) **CLAIM**

We claim the ornamental design for a container closure, as shown and described.

DESCRIPTION

FIG. 1 is a perspective view of a container closure showing the new design;

FIG. 2 is a top view thereof;

FIG. 3 is a side view thereof; the opposite side, front and back being mirror images thereof;

FIG. 4 is a bottom view thereof;

FIG. 5 is a cross-sectional view thereof, taken in the direction of line 5-5 on FIG. 2; and,

FIG. 6 is another cross sectional view, taken in the direction of line 6-6 on FIG. 2.

The broken lines shown in the drawing views are included for the purpose of showing environmental structure that forms no part of the claimed design.
